AUTOMATIC CYCLING SYSTEM FOR PIN
SETTING MACHINES

William J. Hildebrant, Weatogue, and Vincent A. Mala-
testa, Ellington, Conn., assignors to Connecticut Tech-
nical Corporation, Hartford, Conn., a corporation of
Connecticut

Filed June 29, 1962, Ser. No. 206,231
14 Claims. (Cl. 273—43)

This invention relates to pin setting machines for bowling alleys, and deals more particularly with a novel control means for such machines for causing the same to operate automatically in response to the throw of a ball and other events normally occurring in the game.

Various features of the present invention may be applied to various different types of pin setting machines, including machines for setting ten pins, and there is no intention to limit the various features of the invention to use with any particular type of pin setter. In the specification which follows, however, the invention has been shown and described in connection with a particular mechanism for setting duckpins or other type of pins for a game involving the possible throw of three balls in each frame, and various more specific features of the invention are concerned with such machines.

In any pin setting machine the two basic operations performed are a deadwood operation and a resetting operation. The deadwood operation is generally performed after the throw of a ball, other than the last ball of a frame, which leaves standing one or more of the pins, and consists of picking up the standing pins, sweeping the deadwood from the pin deck and into the pit, and thereafter respotting the standing pins for the next ball. The resetting operation is generally performed after the throw of the last ball of a frame and consists of sweeping both deadwood and standing pins, if any, from the pin deck and thereafter spotting a new set of ten pins on the pin deck in the standard triangular array. In previous duckpin setting machines or other setting machines involving the possible throw of three balls in one frame, the control of the machine has generally been effected manually by means of reset and deadwood push buttons located conveniently at the head of the alley and operable by the player or scorekeeper to cause the machine to perform the reset or deadwood operations as desired. Some machines have been made semi-automatic insofar as they automatically reset after the throw of a third ball in a frame, but for various reasons no completely acceptable machine has been made which is entirely independent of manual or pushbutton operation and which will automatically perform a deadwood operation after a first or second ball which leaves standing one or more pins and which will automatically perform a reset operation after a strike or spare situation.

The general object of this invention is therefore to provide a control system for use with a bowling pin setting machine for causing the machine to automatically perform deadwood and reset operations at the required times in response to the throw of a ball and other events of the game. In keeping with this object it is a further object to provide such a control system which is applicable to various different types and constructions of machines and which may be included as part of the original equipment of new machines or added to existing manual or semi-automatic machines, with little or no modification of the machines, to convert such machines to fully automatic operation.

Another object of this invention is to provide an automatic cycling system for a pin setting machine which cycling system is relatively inexpensive to manufacture

2

and apply to a pin setting machine and which is extremely reliable in its operation.

A further object of this invention is to provide a cycling system for a duckpin setting machine which system operates in conjunction with the machine to cause the same to automatically spot a new set of ten pins after a strike or spare and to provide a visual or other indication of the strike or spare.

A still further object of this invention is to provide a cycling system of the character mentioned in the last paragraph including means for detecting the commission of a foul and for using information in the form of electrical signals from the foul detecting means to control the ball count, the deadwood and reset operations and a foul indicator in the proper manner.

A still further object of the invention is to provide an improved means for sensing the approach or passage of a ball toward or through the pin deck and to deliver an electrical signal indicating the same.

Another object of the invention is to provide a device for use with a pin setting machine and including means for giving a visual or other indication of the number of balls which have been thrown in the present frame.

Other objects and advantages of the invention will be apparent from the following description and from the drawings forming a part hereof:

The drawings show a preferred embodiment of the invention and such embodiment will be described, but it will be understood that various changes may be made from the construction disclosed, and that the drawings and description are not to be construed as defining or limiting the scope of the invention, the claims forming a part of this specification being relied upon for that purpose.

35 Of the drawings:

FIG. 1 is a schematic side elevational view of a pin setting machine to which an automatic cycling system embodying this invention is applied and which view shows only the basic elements of the machine, detailed parts having been omitted for clarity.

FIG. 2 is a schematic top plan view of the machine shown in FIG. 1 and which view shows the location of the pin sensing switches relative to the spotted pins, the distributor table, the pin setting table and other parts shown in FIG. 1 being omitted for clarity.

FIG. 3 is a fragmentary vertical sectional view taken through the pin table and shows the structure of the cam means for opening the gripper bars as the distributor table moves forward.

50 FIG. 4 is a fragmentary perspective view showing the arrangement of two limit switches associated with the distributor table.

FIG. 5 is a fragmentary perspective view showing the arrangement of two limit switches associated with the sweep blade drive shaft.

FIG. 6 is a fragmentary perspective view showing the arrangement of four limit switches associated with the drive shaft for moving the distributor table between its forward and rearward positions.

FIG. 7 is a fragmentary perspective view showing the arrangement of four limit switches associated with the drive shaft for the pin table.

FIGS. 8a and 8b taken together constitute one figure 65 illustrating the wiring diagram of an automatic cycling system embodying the present invention and incorporated in the pin setting machine shown in FIGS. 1 and 2.

Section A—General organization of pin setting machine

70 For the purpose of illustration an automatic cycling system embodying the present invention is shown herein as applied to a bowling pin setting machine such as

shown in Patent No. 2,920,891 issued January 12, 1960, and although various parts of said machine are described herein in general terms, reference is made to said patent for a more detailed description of the machine. In the presently illustrated and described pin setting machine, however, the various one revolution clutches shown by the patent have been replaced by electrically operated clutches of the type which are engaged and disengaged respectively in response to energization and de-energization of associated solenoid coils.

Referring to FIGS. 1 and 2, the illustrated pin setting machine is located at the tail end of an associated alley and the major parts thereof are disposed above the pin deck 29 and pit 22 in the usual manner. The various basic components of the machine are carried by a framework 24 and comprise a distributor table 26, a pin table 28 and a sweep blade 30. The sweep blade 30, when operated, moves across the pin deck 29 and sweeps the deadwood and/or standing pins into the pit 22 or gutters 32, 32.

Also included in the pin setting machine, but not shown, are conveyor and elevator means for moving pins and balls from the pit and gutters and for elevating the same above the level of the alley. The balls after being elevated are transferred to a ball guide or chute for return to the head of the alley. The elevated pins are transferred by suitable means to a loading station above the distributor table and from the loading station are fed one by one to the distributor table which includes a set of ten pin receiving cups 34, 34 that are moved in succession past the loading station. The distributor table is movable in a horizontal plane longitudinally of the alley between pin receiving and pin discharging positions. FIG. 1 shows it in its rearward or pin receiving position, and from this position it is movable toward the head of the alley or to the left as viewed in FIG. 1 to a forward or pin discharging position underneath the pin table 28. When the distributor table is in the rearward position shown in FIG. 1 it receives pins from the associated pin elevating means until all of its ten cups 34, 34 are driven in succession past the loading station and after the tenth cup is filled the drive means is disengaged to prevent further movement of the cups.

The distributor table 26 is driven between its rearward and forward positions by a suitable drive mechanism which includes, as shown in FIG. 6, a driven shaft 36, a driving shaft 38 and an electrically operated clutch 40 located between the driven and driving shafts 36 and 38 and operable to bring the driving shaft into and out of driving relationship with the driven shaft. The operation of the drive mechanism is such that one complete rotation of the driven shaft 36 corresponds to a complete cycle of movement of the distributor table. That is, throughout one complete movement of the driven shaft 36 the distributor table is first moved forwardly from its rearward position to its forward position and is thereafter moved rearwardly from its forward position to its initial rearward position.

As mentioned above, the cups 34, 34 are movable relative to the framework of the distributor table and when being filled are moved in succession past a fixed loading station. This movement of the cups 34, 34 is accomplished by a drive shaft which engages the distributor table when the table is in a rearward position and which is rotated through an electrically operated clutch. After all ten cups are filled the clutch is de-energized to stop further movement of the cups relative to the distributor table and loading station.

The pin table 28 serves to lift standing pins from the pin deck during a deadwood operation. In FIG. 2 the pin table is shown in its rest position and it is movable from such rest position to a lowered position close to the pin deck 30. Included in the pin table 28 are four pairs of gripper bars 42, 42 which extend transversely of the associated alley. The two gripper bars of each pair are

carried by brackets 44, 44 which are pivotally connected to the framework of the pin table by associated transverse rods 46, 46. By movement about the axes of the associated rods 46, 46 the two gripper bars 42, 42 of each pair are movable toward and away from each other between relatively closed and relatively open positions. By a suitable linkage the four pairs of gripper bars are connected together so that all four pairs are opened and closed in unison. In FIG. 3 the solid line showing of the pin table illustrates the gripper bars 42, 42 in their relatively open positions. At these positions the bars of each pair are spaced far enough apart as to fit over the head of a pin on the pin deck. When the pin table is moved down toward the pin deck 29, and after the gripper bars 42, 42 have passed over the heads of the standing pins, a suitable actuating means in the pin table moves the gripper bars 42, 42 to their closed positions, as shown by the broken line illustration, whereat the bars grip the necks of the standing pins. The pin table may now be lifted from its lowered position and in so doing the gripper bars 42, 42 will lift the standing pins from the pin deck to allow movement of the sweep blade 30 over the pin deck to remove any deadwood therefrom. After the sweep blade completes its motion over the pin deck, the pin table is again lowered and as the pins carried by the pin table engage the pin deck the gripper bars 42, 42 are again moved by the actuating means to their open positions so that the pin table may now be raised to its rest position leaving the previously lifted pins spotted in their original positions on the pin deck.

The pin table is driven in this vertical movement by a suitable drive means which, as shown in FIG. 7, includes a driven shaft 48, a driving shaft 50 and an electrically operated clutch 52 located between the driving and driven shaft. One complete rotation of the driven shaft 48 corresponds to one complete cycle of movement of the pin table 28. The arrow in FIG. 7 represents the direction in which the driven shaft 48 is driven by the drive shaft 50 and for convenience this direction is considered to be the forward direction. When the pin table is in its rest position as shown in FIG. 2 it is located slightly below its uppermost position and it is held in this position and against retrograde or reverse downward movement and against the force of gravity and an associated spring, by an associated latch mechanism, not shown. The pin table therefore may be lowered from its rest position by either releasing the latch and allowing the table to drop under this influence of gravity and the associated spring, in which case the driven shaft 48 rotates freely in reverse direction, or by energizing the clutch 52 so that the driving shaft 50 rotates the driven shaft 48 in the forward direction and in which case the pin table is first raised slightly from its rest position to its uppermost position and then driven downwardly from its uppermost position to the pin deck.

In addition to lifting the standing pins from the pin deck during a deadwood operation, the pin table 28 is also used during a reset operation for spotting a new set of ten pins on the pin deck in the desired triangular array. During this reset operation the distributor table 26 is first moved to its forward position underneath the pin table 28. In the distributor table the pins are oriented by the cups 34, 34 in the desired triangular array. After the distributor table reaches its forward position the distributor table trips the latch holding the pin table in its rest position and the latter drops freely under the force of gravity and the associated spring toward the distributor table until the gripper bars 42, 42 receive the necks of the pins carried by the distributor table. At this time the gripper bars 42, 42 are closed by the associated actuating mechanism and the drive clutch 52 is thereafter energized to rotate the shaft 48 in the forward direction to raise the pin table and the pins from the distributor table. As the pin table moves upwardly the distributor table is retracted towards its initial rearward

position and the drive shaft 48 is continued in its rotation so that the pin table after passing its uppermost position is lowered toward the pin deck. When the pins reach the pin deck the gripper bars are opened to release and spot the pins on the pin deck, and the pin table is thereafter returned empty to its rest position for subsequent use in a following deadwood or reset operation.

Associated with the pin setting machine and forming a part of the cycling system of the present invention is a pin sense switch assembly 54 which is fixed to the framework 24 of the pin setting mechanism above the pin table 28. Included in the switch assembly 54 is a group of ten switches 56, 56 having operating levers 58, 58 arranged to respectively engage the heads of the various pins carried by the pin table when the pin table is in or near its uppermost position. This is shown, for example, in FIG. 2 from which it will be noted that for each pin position there corresponds a separate switch operating lever 58 so that if any one pin is lifted by the pin table the associated operating lever 58 will be moved by the pin to actuate the associated switch 56 when the pin table reaches or nears its raised position.

The pin setting machine is located behind a mask or wall 60 and located on the forward side of the mask are three lamps 62, 62 operated by the cycling system of this invention to provide a visual indication of the ball count. Also included as part of the cycling system, and hereinafter described in more detail, is a means for detecting the passage of a ball towards the pin deck. In the present instance this means comprises a light source 64 located on one side of the alley and a photocell unit 66 located on the other side of the alley and arranged to receive a beam of light 68 from the light source. The light source 64 and the photocell unit 66 are so arranged that the light beam 68 will be broken to operate the detecting means by a ball passing down the alley or down either one of the two gutters 32, 32.

Without the automatic cycling means of the present invention, and as shown by the above mentioned patent, the pin setting machine may be operated manually by means of reset and deadwood pushbuttons located at the head of the alley. Pushing the reset pushbutton causes the machine to perform a reset operation and pushing the deadwood pushbutton causes the machine to perform a deadwood operation. In the normal reset operation, as performed for example in response to pushing the reset pushbutton, the sweep blade 30 is moved across the pin deck to remove therefrom any dead or standing pins. At the same time, the distributor table 26 is moved forwardly and the pin table 28 is lowered onto the distributor table to receive a new set of pins. The pin table is then raised from the distributor table and the distributor table returned to a rearward position. Thereafter the pin table is lowered to the pin deck to spot the new set of pins thereon and is then returned to its rest position. During a normal deadwood operation, as performed for example in response to pushing the deadwood pushbutton, the distributor table remains stationary and the pin table 28 is lowered to grasp and lift from the pin deck the standing pins. The sweep blade 30 is then operated to remove any deadwood from the pin deck and after the blade moves from the pin deck the pin table is again lowered to respot the standing pins on the pin deck. Once the pins are released the pin table is again returned to its rest position.

In accordance with the present invention, when the automatic cycling system is used in conjunction with the pin setting machine the machine is automatically commanded to perform a reset operation after the passage of a third ball through the pin deck. Also, the machine is commanded to initiate, but not necessarily complete a deadwood operation in response to the passage of a first or second ball through the pin deck. After a first or second ball passes through the pin deck the pin table 28 moves downwardly to grasp and lift any standing

pins from the pin deck and as it returns from its lowered position the appropriate operating lever or levers 58, 58 of the pin sense switch assembly 54 engage the heads of the pin or pins, if any, carried by the pin table. If these operating levers sense the presence of one or more pins in the pin table, as a result of one or more switches being operated, the pin setting mechanism is permitted to complete a normal deadwood cycle with the pins in the pin table being resotted on the pin deck after the sweep blade 30 completes its sweeping operation. On the other hand, if the pin sense switch assembly determines that no pins are in the pin table, as a result of none of the switches being operated, the pin setting machine is commanded at that point to spot a new set of pins on the pin deck.

Each time the pin table is lowered onto the pin deck or distributor table the associated gripper bar actuating mechanism changes the state of the gripper bars. That is, the gripper bars are moved either from their open to their closed positions or from their closed to their open positions. At the start of a deadwood operation the gripper bars are in an open condition and therefore when the pin sense switch assembly makes its determination that no pins are in the pin table the gripper bars are closed as a result of the pin table having been first lowered to and raised from the pin deck. Therefore, in order that the pin table may be used to reset a new set of pins the gripper bars must be returned to their open condition. To provide for this opening of the gripper bars one of the transverse rods 46, 46 as shown in FIG. 3 has associated therewith a bar 70 which is fixed to the rod by a suitable means such as a U-bolt 72. The bar 70 engages the associated gripper bar 42 so as the bar 70 is rotated in the clockwise direction about the axis of the rod 46 the gripper bar 42 is moved from its closed position as indicated by the solid lines to its open position as indicated by the broken lines. All of the gripper bars 42, 42 move in unison and therefore movement of the illustrated gripper bar to its open position corresponds to movement of all of the gripper bars to their open positions. Associated with the bar 70 is an arm 74 which is pivotally connected to the rod 70 as at 76 and which normally hangs downwardly from the bar 70 with its upper edge 78 in engagement with the associated transverse rod 46. On the lower end of the arm 74 is a roller 80 which cooperates with a cam 82 mounted on the distributor table 26. As the distributor table moves forwardly the inclined surface 84 of the cam 82 engages the roller 80 and moves the same to cause the gripper bar 42 to be moved to its open position. After the gripper bar is opened the cam 82 passes forwardly beyond the arm 74. In the return movement of the distributor table the arm 74 pivots freely about the pivot point 76 to the position shown by the broken lines in FIG. 3 to permit passage of the cam 84 without returning the gripper bars to their closed positions.

Section B—General organization of automatic Cycling system

The wiring diagram of the automatic cycling system embodying the present invention is shown in FIGS. 8a and 8b, which figures should be placed side by side to provide one single composite illustration. The portion of the wiring diagram shown in FIG. 8b relates solely to the automatic cycling system and the portion of the wiring diagram shown in FIG. 8a includes limit switches, clutches and the like which are or may be part of a manually operated pin setting machine. FIG. 8a also includes other parts which form part of the automatic cycling system and which cooperate with said limit switches, clutches and the like of the pin setting machine to provide the automatic operation desired.

Referring first to FIG. 8a, the designation LS has been given to limit switches contained in the pin setting machine and which limit switches provide the automatic

cycling system with information concerning the condition of the machine at any particular moment. In this figure LS-5 and LS-4 are limit switches which are associated with the distributor table and which are operated when the distributor table becomes completely filled with ten pins. Referring to FIG. 4, the two switches LS-4 and LS-5 are operated respectively by two cams 86 and 88 fixed to a rotatable shaft 90 which is biased by a spring, not shown, to the illustrated position. Fixed to one end of the shaft 90 is a finger 92 which extends into the path of pins carried by the cups of the distributor table. The shaft 90 and finger 92 are so located on the distributor table that as soon as the tenth and last cup of the distributor table is filled with a pin such cup is moved toward the finger 92 which engages the pin and rotates the shaft 90 to operate the limit switches LS-4 and LS-5 to indicate the filled condition of the distributor table.

As shown in FIG. 5 the limit switches LS-8 and LS-13 are arranged to be operated by cams 94 and 96 carried on the driven shaft 98 of the sweep blade drive mechanism. As the sweep blade shaft 98 rotates, the switches LS-8 and LS-13 are therefore operated by the cams to provide an indication of the position of the sweep blade. Also included in the sweep blade drive means is a driven shaft 100 and an electrically operated clutch 102 located between the driving and driven shafts. As shown in FIG. 6 the limit switches LS-11, LS-14, LS-3 and LS-6 are operated by cams 104, 106, 108 and 110 fixed to the driven shaft 36 of the drive means for moving the distributor table between its rearward and forward positions. These limit switches therefore provide an indication of the position of the distributor table. As shown in FIG. 7 the limit switches LS-10, LS-7, LS-15, LS-12 and LS-9 are operated by cams 112, 114, 116, 118 and 120 fixed to the driven shaft 48 of the pin table drive means and therefore provide for an indication of the position of the pin table.

The various electrically operated clutches associated with the sweep blade, the distributor table and the pin table are illustrated at 102, 40 and 52 in FIG. 8a. The clutch illustrated at 122 is also associated with the distributor table and serves when energized to drive the pin cups 34, 34 past the loading station.

Included in the automatic cycling system is a means for detecting the passage of a ball toward or through the pin deck and for producing an electrical signal in response to such passage. Various different detecting means may be employed, but in the present instance the means employed, as shown by FIG. 8b, includes the light source 64 which may be a lamp energized by six volts A.C. and which, as shown in FIG. 2, is located on one side of the alley some distance forwardly of the pin deck. The light source 64 emits a beam of light which extends across the alley and strikes a photosensitive cell or other photosensitive device 66. The device 66 is connected between the base and the emitter terminals of a transistor 124 which has its collector terminal connected as shown with the grid of a thyratron tube 126. When a ball passes through the light beam it reduces the voltage appearing across the terminals of the photosensitive device 66 and thereby reduces the collector current of the transistor. This reduction of the collector current, in turn, causes the grid of the thyratron to rise toward a positive voltage. The resistor 128 prevents the grid voltage from rising much above zero volts as grid voltage is drawn. However, before this value is reached the cathode-to-grid voltage of the thyratron passes through zero, the gas in the tube ionizes, and conduction through the tube begins. This conduction of the thyratron does not cease until the plate circuit is opened. The thyratron therefore in essence constitutes a switch which is closed in response to the passage of a ball.

Also included in the automatic cycling system is a means for counting the number of balls thrown by a given player in one frame and for producing an electrical output signal indicative of the ball count. In the present

instance this counting mechanism comprises a stepping switch having an operating coil S and a group of step terminals S₀, S₁, S₂ and S₃ which are engageable in succession by a wiper 130. The terminal S₀ constitutes the home terminal of the stepping switch and the terminals S₁, S₂ and S₃ constitute three active terminals which are engaged by the wiper 130 to produce signals indicative of the ball count. The wiper 130 is moved from one step terminal to the next in response to the energization and de-energization of the stepping switch coil S, and the switch is of the back-acting type whereby the wiper 130 is not moved from one step terminal to the next until the coil is de-energized. Also associated with the stepping switch are a set of off-normal contacts S_a and S_b and a set of interrupter contacts S_c and S_d. When the stepping switch is in its home position the contacts S_a and S_b are in the positions illustrated in FIG. 8b and when the stepping switch coil is de-energized the interrupter contacts S_c and S_d are in the positions shown in FIG. 8b.

Section C—Manual deadwood operation without automatic cycling system

One of the features of the present invention is that the pin setting machine may be operated with or without the automatic cycling system. If it is desired to operate the machine manually by means of the reset and deadwood pushbuttons 132 and 134, respectively, and without having any indication of the ball count or operation of the foul detector, the automatic cycling system is turned off by turning the switch 136 to the "off" position. With the switch 136 turned off all of the switches and other parts of the system are in the positions shown in FIGS. 8a and 8b when the pin setting machine is at rest and ready for its next commanded operation. At this time the distributor table is in its rearward position and has its cups 34, 34 not entirely filled with pins, the pin table is in its elevated rest position, and the sweep blade is positioned alongside the gutter as shown in FIGS. 1 and 2. Also at this time the various drive shafts and cams associated with the distributor table, pin table and sweep blade are in the relative positions shown in FIGS. 4, 5, 6 and 7.

With the switch 136 in the "off" position a deadwood operation is initiated by pushing the deadwood pushbutton 134. This energizes the coil of relay CR-2 through the closed contacts LS-7b, LS-9 and CR-1a and operates the associated contacts CR-2a, CR-2b and CR-2c. This energization of CR-2 therefore in turn closes a holding circuit to the latter relay through contacts P_d, LS-8, and CR-2a and also energizes the coil of relay CR-3 through the contacts CR-2b. The energization of relay CR-3 in turn closes the contacts CR-3a to complete a holding circuit to the relay CR-3 through LS-10 to hold CR-3 energized after the relay CR-2 is released. Energization of CR-3 also closes contacts CR-3b and thereby energizes the pin table drive clutch 52 so that the pin table is set in motion. At the beginning of this motion the pin table is in its rest position empty of pins and the pin gripping bars 42, 42 are in their open positions. It will also be noted that when the relay CR-2 is energized a warning lamp 140 will also be energized to provide an indication that the setting machine is in operation and that no ball should be thrown.

As the pin table starts in its movement the limit switch LS-10 is opened momentarily by the cam 112 but this has no effect due to the closed condition of CR-2b. When the pin table reaches or nears its lowermost position the limit switch LS-15 is operated by the cam 116 closing contacts LS-15a and opening contacts LS-15b. The closing of the contacts LS-15a energizes the sweep blade drive clutch 102 and sets the sweeper blade in motion. Then as the sweep blade starts in its motion the limit switch LS-13 is operated by the cam 96 and this maintains the sweep blade drive clutch 102 energized after LS-15 is released by further movement of the pin table. As the sweep blade begins its sweeping motion the pin table also rises from the pin deck. Near the uppermost

position of the pin table the limit switch LS-10 is again momentarily operated, but at this time the sweep blade has not yet completed its sweeping motion and the contacts CR-2b are therefore still closed with the result that the clutch 52 remains energized through the contacts CR-2b and the pin table starts down again. Also at or near the uppermost position of the pin table the heads of the lifted pins are brought into engagement with the corresponding pin sense switch operating levers 58, 59 and one or more of the pin sense switches 56, 56, depending on the number of lifted pins, are closed. Also associated with the pin table is a pin table switch 138 which is arranged for operation in response to movement of the table to its uppermost position and after the operation, if any, of the pin sense switches 56, 56. In this manual cycle, however, the switches 56, 56 and 138 have no effect on the operation of the pin setting machine.

The sweep blade moves from the pin deck shortly before the pin table reaches its lowermost position and as the pin table does reach this position the gripper bars are operated by the associated actuating mechanism so as to be returned to their open positions, thereby releasing the pins for placement on the pin deck. At this time the limit switch LS-15 is again operated but this does not start a new sweep blade cycle since the sweep blade is still in motion from previous closing of LS-15 and the clutch 102 is at this time energized through the closed contacts LS-13b.

After the pins are resotted on the pin deck by the opening of the gripper bars, the pin table starts to rise again and as it rises the sweep blade completes its motion. As the sweep blade nears the end of its motion the cam 94 operates the limit switch LS-8 momentarily and thereby breaks the holding circuit to the relay CR-2 and releases the latter. This also extinguishes the warning lamp 40. At the end of its sweeping motion the limit switch LS-13 is returned to its initial state by the cam LS-13 which de-energizes the sweep blade drive clutch 102 and stops further movement of the sweep blade.

When the pin table reaches its uppermost position the limit switch LS-10 is again operated and, since the contacts CR-2b are now open as a result of the de-energization of relay CR-2, CR-3 is de-energized and this in turn causes the de-energization of the pin table clutch 52 and stops further movement of the pin table just before the pin table reaches its uppermost position. The pin table thereafter settles downwardly slightly to its rest position in which position it is held by the associated latch mechanism.

Section D—Manual reset operation without automatic cycling system

A reset cycle with the automatic cycling system switch 136 turned "off" is initiated by pushing the reset pushbutton 132. This, it will be noted energizes the coil of the relay CR-1 through the closed contacts LS-7b, LS-9 and CR-2c. At the same time as the relay CR-1 is operated the warning lamp 140 is also energized to indicate that the pin setting mechanism is in operation and that no ball should be thrown for the time being. Operation of the relay CR-1 closes contacts CR-1c which completes a holding circuit to the coil of CR-1 through LS-8 and P_d. If at this time the cups 34, 34 of the distributor table are not already full of pins the pin cup clutch 122 is energized to move the cups 34, 34 past the loading station for the purpose of receiving pins. When the distributor table does become filled with pins the shaft 90 is moved by the finger 92 so that the limit switch LS-4 is opened by the cam 86 to de-energize the clutch 122 and the limit switch LS-5 is closed by the cam 88.

Closing of the limit switch LS-5 completes a circuit through the now closed contacts CR-1b to energize the distributor table clutch 40. Energization of this clutch

starts the distributor table moving forwardly and as this occurs the limit switch LS-3 opens followed by a later closing of the limit switch LS-4 as the finger 92 moves out of engagement with the number ten pin as a result of the distributor table movement. This has no effect on the system other than the fact that the prior opening of the limit switch LS-3 prevents energization of the pin cup clutch 122 as a result of the closing of the limit switch LS-4.

As the distributor table moves forwardly LS-6 is also closed and shortly thereafter LS-5 is opened. The closing of LS-6 maintains energization of the distributor table clutch 40 despite the subsequent opening of the limit switch LS-5. As the distributor table reaches its forwardmost position LS-14 is closed by the cam 106 to energize the sweep blade drive clutch 102, and after the sweep blade starts to move the limit switch LS-13 is operated to maintain energization of the clutch 102 after the subsequent reopening of the limit switch LS-14 as the distributor table moves rearwardly. At the end of the sweep blade motion LS-13 shifts back to its initial state and the sweep blade drive is stopped.

As the distributor table reaches its forward position underneath the pin table the limit switch LS-6 is again opened by the cam 110 and this opens the circuit to the distributor table drive clutch 40 and to stop the distributor table at such forward position. At the same time the movement of the distributor table to its forward position mechanically releases the latch on the pin table and allows the same to drop by gravity and spring force onto the distributor table with the shaft 48 rotating in the reverse direction. When the pin table reaches the distributor table the gripper bars pass over the heads of the pins in the latter table and are closed relative to one another so as to be brought into gripping relationship with the pins. As mentioned, when the pin table does drop towards the distributor table the drive shaft 48 is rotated in the reverse direction and this causes the limit switches LS-9 and LS-12 to change state. Closing the limit switch

LS-12 energizes the relay CR-3 and through the associated contact CR-3b this energizes the pin table drive clutch 49. The opening of the limit switch LS-9 prevents the initiation of a new deadwood or reset cycle while the pin table is in motion. The pin table rises again, because of the energization of the clutch 40, and lifts the new set of pins with it. Energization of the relay CR-3 also closes contacts CR-3a which completes a holding circuit through LS-10 to maintain the pin table drive clutch energized to raise the pin table. As the pin table near its uppermost position LS-7 is momentarily operated and closes a circuit through CR-1b to energize the distributor table clutch 40 and thereby initiate rearward movement of the distributor table. As the latter does move rearwardly LS-6 is again closed to maintain the energization of the clutch 40 for the full extent of the rearward motion.

When the distributor table does reach the rearward limit of its motion LS-6 is again operated to de-energize the clutch 40. Also as the pin table nears its uppermost position LS-10 is opened so that the drive clutch 52 is de-energized to prevent further movement of the pin table until the distributor table nears its full rearward position. As the distributor table does near its full rearward position the limit switch LS-11 is operated momentarily and this operates the pin table clutch 52 until the limit switch LS-10 is again closed. When the limit switch LS-10 is closed the holding circuit for the relay coil CR-3 is again established and the pin table continues moving downwardly past the level of the distributor table which is now retracted.

When the pin table strikes or nears the pin deck the gripper bars are opened by the associated actuating mechanism to release the pins for replacement on the pin deck. The timing is such that at this time the sweep blade is removed from the pin deck area so as not to interfere with the spotting of the pins on the pin deck, but is also

not yet completely returned to the end position of its movement. Therefore, as the pin table reaches its lowermost position, it operates the limit switch LS-15 momentarily but this has no effect since the sweep blade is still in motion and the limit switch LS-13 is therefore still operated.

The pin table rises from the pin deck, due to the closed condition of the switch LS-10 and the contact CR-3a, empty of pins and when it nears its uppermost position it first closes and then opens the limit switch LS-12 to no effect. The limit switch LS-11 is now open due to the distributor table being in its full rearward position. Just before it reaches its uppermost position the limit switch LS-10 is opened and this de-energizes the relay CR-3 and consequently de-energizes the pin table drive clutch 52. Thereafter, the pin table settles back to its rest position and the associated latch engages the same to hold it in its rest position against the force of gravity and the associated spring. Now as the sweep blade nears the end position it momentarily opens LS-8 which releases CR-2. Shortly thereafter LS-13 is operated to reopen LS-13b and stop the sweep blade motion.

Section E—Manual deadwood operation with automatic cycling system

The design of the automatic cycling system is such that even after the automatic system is turned "on," by turning the switch 136 to the "on" position, the pin setter may be operated manually by pressing the reset and deadwood pushbuttons 132 and 134.

When the switch 136 is turned to the "on" position the relay coil B is energized with the result that the contacts B_a and B_c are closed and the contacts B_b are opened. This operation of the relay B has no effect on the manner in which the deadwood operation is performed as a result of pushing the deadwood pushbutton 134. That is, pushing the button 134 energizes the relay CR-2 through the contacts LS-7b, LS-9 and CR-1a and thereafter the deadwood operation proceeds in the same manner as described above in Section C.

Section F—Manual reset operation with automatic cycling system

Included in the automatic cycling system are the indicator lights 62, 62 which serve to provide a visual indication of the ball count and which are operated by the stepping switch S. These lights and the stepping switch do not function when the pin setting machine is operated without the automatic cycling system. When the cycling system is used, however, it is necessary that each time the pin setting machine performs a reset operation that the ball count lamps 62, 62 be extinguished and that the stepping switch be returned to its initial or home condition so as to be reset for use in providing a proper ball count for the next player. Therefore, the manner of achieving manual reset with the automatic cycling system on is not exactly the same as the manner in which it is achieved with the automatic cycling system off.

With the switch 136 turned "on" and the relay B energized, pressing the reset button 132 energizes the relay A through the contacts LS-7b, LS-9 and B_c. Energization of the relay A completes a circuit to the coil of relay X through the now closed contacts A_a, and through the same contacts A_a also energizes the relay Z. As shown the coil of relay X has associated therewith a capacitor 142 which is connected across the end terminals of the coil and which functions to make the relay X slow-operating and slow-releasing. Operation of the relay closes contacts Z_d and thereby operates relay Y and completes a holding circuit to relays Y and Z through the off normal contact S_b of the stepping switch. Relay Y has associated therewith a capacitor 144, a resistor 146 and a pair of contacts Y_b and Y_c which operate to make the relay Y slow-operating and fast-releasing. The capacitor 144 is however larger than the capacitor 142 so that the relay Y

is slower operating than the relay X. Therefore the relay Y operates some time after relay X. Operation of relay Y opens contacts Y_a to break the circuit to relay X and after some delay relay X thereafter releases. After relay X releases contacts X_a close and thereby complete a restore circuit to the stepping switch coil S through the contacts Z_b, the interrupter contacts S_c and the off normal contacts S_b. The stepping switch is therefore operated to step the wiper 130 to the home or S₀ terminal and when the wiper does reach the home position the off normal contacts S_b are opened thereby opening the holding circuit to relays Z and Y and releasing the latter. After this occurs relays X, Y and Z are all in their initial unoperated condition and the stepping switch is restored.

From the foregoing it will be observed that due to the operating and release characteristics of the relays X, Y and Z all three relays are simultaneously energized for a brief interval of time before being returned to the unoperated condition. During this period of simultaneous energization the contacts X_c and Y_d and Z_f are closed which completes a circuit to the relay CR-1 through the contacts LS-7b, LS-9, F_c, Z_e and CR-2c. After the relay CR-1 is operated the reset operation continues in the same manner as set forth above in section D.

Section G—Automatic deadwood cycle after first ball with one or more pins left standing

Although the pin setting machine may be operated manually through the reset and deadwood pushbuttons 132 and 134, respectively, when the automatic cycling system is turned on, the use of these buttons is usually unnecessary and the automatic cycling system will operate to command deadwood and reset operations at the proper times throughout the course of the game. For example, the automatic cycling system includes means for causing the pin setting machine to perform a deadwood operation after the throw of a first or second ball by a given player in one frame and which ball leaves standing one or more pins. The manner in which this is accomplished is described below.

Assume that the ball thrown is the first ball, therefore before the ball is thrown the stepping switch wiper 130 is on the home terminal S₀ and the lamps 62, 62 are all extinguished. The ball in approaching the pin deck thereafter passes through the light beam 68 and, as described above, causes the thyratron 126 to conduct. When thyratron conduction begins a current flows through the coil of the stepping switch S. Since the stepping switch S is a back acting switch this energization of the coil does not immediately step the wiper 130, but it does close the interrupter contacts S_d to complete a circuit to the relay X through the closed contacts Z_c. After the circuit to the relay X is closed the relay operates a short time thereafter. The operation of the relay X opens the contacts X_a which opens a circuit to the plate of the thyratron and thereby extinguishes the latter and de-energizes the coil of the stepping switch S. The de-energization of the stepping switch S causes it to step the wiper 130 from the home terminal S₀ to the first step terminal S₁. This in turn causes the first indicator light 62 to be lighted to represent the passage of the first ball.

Also as the relay X is operated the contacts X_b are closed to complete a circuit to the relay Y. A predetermined time after this circuit is completed the relay Y operates to open the contacts Y_a and Y_b and close the contacts Y_c and Y_d. Opening of the contacts Y_a breaks the circuit to the relay X and, the X relay being slow-release, the contacts associated therewith are switched back to their initial positions a predetermined time after the latter circuit is broken. When this occurs the contacts X_a are closed and the contacts X_b and X_c are opened. Closing of the contacts X_a conditions the thyratron for firing upon the passage of the next ball. Opening of the contacts X_b breaks the circuit to the relay Y, thereby de-energizing the latter relay and returning its contacts back to their initial

positions. After this occurs both the relay X and the relay Y are in their initial unoperated conditions and ready for operation in response to the passage of the next ball or other events. It should be noted, however, that before the Y relay is released both the X and Y relays are energized simultaneously for a given amount of time due to the operating and release procedure described. During this period of simultaneous operation the contacts X_e and Y_d are simultaneously closed and complete a circuit to the relay CR-2 through the contacts LS-7b and LS-9, F_c , Z_e and CR-1a. Closing of the relay CR-2 initiates a deadwood operation which is then carried to completion in the same manner as it is in the description set forth above in Section C.

If the ball thrown happens to be the second ball rather than the first, the same results will be obtained except that when the stepping switch S is stepped the wiper 130 will be moved from the first step terminal S_1 to the second terminal S_2 to light the second indicator lamp 62. It will be observed that the arrangement of the lamps 62, 62 is such that when the wiper 130 is on the second step terminal S_2 both the first and second indicator lamps will be lighted.

Section H—Automatic reset cycle after third ball

When the automatic cycling system is turned on as a result of the switch 136 being placed in the "on" position it will operate to automatically command the pin setting machine to perform a reset operation after the throw of a third ball by a player in a given frame.

Before the third ball is thrown the stepping switch wiper 130 is in engagement with the second step switch terminal S_2 to provide an indication of a ball count of two. Now, when the third ball is thrown the ball again breaks the light beam 68 and causes conduction of the thyratron 126 and energization of the stepping switch coil S. Energization of the stepping switch coil S closes the interrupter contacts S_d and thereby completes a circuit to the relay X through the contacts Z_c . When the relay X operates the contacts X_a are opened and the contacts X_b are closed. Opening of the contacts X_a immediately de-energizes the stepping switch coil S, extinguishes the thyratron and steps the wiper 130 from the step terminal S_2 to the step terminal S_3 thereby lighting all three lamps 62, 62 and also energizing the relay Z through the line 148. Closing of the contact X_b completes a circuit to the relay Y which due to its slow-operate characteristic operates after the operation of the relay Z. Operation of the relay Z completes a holding circuit to the relays Y and X through the now closed contacts Z_d and the off-normal contacts S_b of the stepping switch. Operation of the relay Y opens the contacts Y_a and thereby breaks the circuit to the relay X which therefore releases a predetermined time after the opening of the contacts Y_a . When the relay X releases the contacts X_a are closed and this completes a restore circuit to the coil of the stepping switch S through the contacts Z_b , the interrupter contacts S_e and the off-normal contacts S_b . The stepping switch S is therefore operated to step the wiper 130 to the home terminal S_0 after which the off-normal contacts S_b are opened to inhibit any further restoring action. Movement of the wiper 130 to the home position in turn extinguishes all three ball count indicator lamps 62, 62. After the off-normal contacts S_b do open the holding circuit to the relays Y and Z is also opened so that the latter two relays are returned to their initial unoperated conditions. It will also be noted that during the above described operation that all three relays X, Y and Z are operated simultaneously for a given period and during this period of simultaneous operation the contacts X_e , Y_d and Z_f are closed to complete a circuit to the relay CR-1 through the contacts LS-7b, LS-9, F_c and CR-2c. After the relay CR-1 is energized a reset operation is performed in the same manner as described above in connection with Section B.

In this regard it should also be noted that the relay Z

acts as a means for controlling the restoration of the stepping switch S and that when the relay Z is operated the stepping switch will be restored. It will also be noted that the contacts Z_e and Z_f of the relay Z serve as a cycle selection switch for selectively routing the command signal produced by the simultaneous closing of the contacts X_e and Y_d to either the control relay CR-1 to initiate a reset cycle of machine operation or to the control relay CR-2 to initiate a deadwood cycle of machine operation.

10 Section I—Automatic reset following strike on first ball

Following a strike on the first ball the automatic cycling system operates to command the pin setting machine to spot a new set of pins on the pin deck in readiness for the next player, and to produce a visual indication of the strike. Actually, in the present instance after the passage of the ball the pin setter is commanded to initiate a deadwood operation and during the course of the deadwood operation when the pin sensing switches determine that no pins have been left standing on the pin deck this information is used to interrupt the deadwood operation and to cause the pin setting machine to thereafter carry out the operation of placing a new set of pins on the pin deck. Since the complete operation is not entirely similar to either the deadwood or the reset operations described above in sections C and D the operation may be referred to as a "modified reset" cycle. The manner in which this cycle is performed is described below.

Before the ball is thrown the wiper 130 of the stepping switch is engaged with the home terminal S_0 and none of the ball count lights 62, 62 are lighted. The passage of the ball down the alley breaks the light beam 68 and causes conduction of the thyratron 126 and energization of the step switch coil in the same manner as described above in Section E. This in turn, as also described in Section E, causes operation and release of the relays X and Y in such a manner that for a given period of time both relays are energized simultaneously so as to cause simultaneous closing of contacts X_e and Y_d and thereby energization of the relay CR-2 through the contacts LS-7b, LS-9, F_c , Z_e and CR-1a. Operation of the relays X and Y also causes stepping of the step switch to move the wiper 130 from the home terminal S_0 to the first step terminal S_1 . Energization of the relay CR-2 initiates a deadwood operation and as described in Section E causes energization of the pin table drive clutch 52 to set the pin table in motion downwardly toward the pin deck. At this time the pin table is empty of pins and the pin gripping bars 42, 42 are in their open positions. As the pin table reaches its lowermost position the pin gripping bars are closed by the associated actuating mechanism and at the same time the limit switch LS-15 is momentarily operated to start movement of the sweep blade. The sweep blade thereafter starts its sweeping motion while the pin table rises from the pin deck, but since all pins have been knocked down the pin table takes with it no pins. As the sweep blade starts its motion, the limit switch LS-13 is operated to maintain the drive clutch 102 energized after the limit switch LS-15 is released by the rising movement of the pin table.

When the pin table reaches or nears its uppermost position, the pin table switch 138 is opened, and at the same time all of the pin sensing switches 56, 56 are also open due to the fact that no pins are held in the pin table. As a result of this a shunt circuit provided by line 150 to the relay P is opened to permit operation of the latter relay, and since at this time the limit switch LS-15 is in its initial position the relay P is energized through the closed contacts LS-15b. The energization of the relay P closes contacts P_b , P_c and P_e and opens contacts P_a , P_d and P_f . Opening of the contacts P_f prevents the relay P from being immediately shunted out by the reclosing of the switch 138. Opening of the contacts P_a removes a shunt circuit provided by the line 152 from the relay W and allows W to operate through the first stepping switch

terminal S_1 which now is in engagement with the wiper 130. Closing of the contacts P_b together with the closing of the contacts W_b brought about by the energization of the relay W lights the strike indicator lamp 154. Opening of the contacts P_d breaks the circuit to the relay CR-2. This in turn opens the contacts CR-2b and since the pin table is now near its uppermost position LS-10 is open so that the pin table clutch 52 is de-energized and the pin table settles to its rest position in which it is held by the associated latch. Releasing of the relay CR-2 therefore terminates the deadwood cycle before it runs its normal full course. It will be noted that when the cycle is stopped by the release of CR-2 the pin setting machine is in substantially the same condition as it is at the beginning of any normal deadwood or reset cycle except that the gripper bars 42, 42 are in their closed positions.

Release of the relay CR-2 does not, however, end the modified reset cycle. Energization of the relay P also causes energization of the relay A due to the closing of the contacts P_e . This energization of relay A in turn causes the relays X , Y and Z to be operated and released in the same manner as described above in Section F to provide for a period of simultaneous energization of all three relays and thereby provide for simultaneous closing of the contacts X_c , Y_d and Z_f and as a result of this provides for the momentary energization of relay CR-1. The energization of the relay Z also provides for restoration of the stepping switch in the same manner as described in Section F.

The momentary energization of CR-1 does not have any effect since the open condition of the contacts P_d prevents the closing of a holding circuit by the closing of the contacts CR-1c. Therefore when either the contacts X_c , Y_d or Z_f are reopened relay CR-1 is released. The energization of the relay P , however, closes the contacts P_e which energizes the distributor table clutch 40 provided the distributor table pin cups are filled with pins and the switch LS-5 therefore closed.

When the distributor table does reach its forward position the latch holding the pin table is mechanically released so that the pin table falls onto the distributor table to grasp a new set of pins. As the pin table does reach the distributor table LS-12 is operated to energize CR-3 and, through the contacts CR-3b, the pin table drive clutch 52. The pin table therefore starts to rise and as it rises the clutch 52 is held operated through closed contacts LS-10 and CR-3a. As the pin table nears its uppermost position LS-7 is operated to start the distributor table moving rearwardly and LS-10 is operated to stop movement of the pin table, the latter settling to its rest position while the distributor table moves rearwardly. When the distributor table nears its rearward position the limit switch LS-11 is operated to again energize the pin table clutch 52. After the clutch 52 is energized for a short time LS-10 recloses to maintain energization of clutch 52 after LS-11 reopens. Under the influence of LS-10 the pin table is thereafter driven downwardly to the pin deck to spot the new set of pins and is thereafter returned empty to its raised rest position at which time LS-10 opens and the cycle is ended. In this regard it should be noted that as the pin table reaches the pin deck it operates LS-15. Closing of the associated contacts LS-15a has no effect and does not start a new motion of the sweep blade due to the now open condition of the contacts CR-2d. Opening of the contacts LS-15b however releases the relay P and closes the contacts P_f so that after the contacts LS-15b reclose the relay P remains shunted through the now closed contacts P_f and LS-13a. Therefore when the pin table does reach its rest position all relays and other parts of the system are in their initial conditions and ready for the start of a new frame.

Section J—Automatic reset following spare on second ball

Following a spare on the second ball the automatic

75

Assume now that the ball thrown is the second ball

cycling system operates to command the pin setting machine to spot a new set of pins on the pin deck in readiness for the next player and to provide a visual indication of the spare.

Before this ball is thrown the wiper 130 of the stepping switch is engaged with the first step terminal S_1 and the first ball count light 62 is lighted. The passage of the ball down the alley breaks the light beam 68 and in the same manner as described in the preceding section causes the wiper of the stepping switch to be stepped to the second step terminal S_2 , lighting both the first and second ball count lamps 62, 62, and also causes energization of the relay CR-2 to initiate a deadwood cycle. As the pin table is raised from the pin deck, however, none of the pin sense switches 56, 56 is closed, due to the absence of pins in the pin table, and this followed by the opening of the switch 138 causes operation of the relay P by opening the shunt circuit provided by line 150, the contacts LS-13a also being open at this time due to the sweep blade being in motion.

Operation of the relay P closes contacts P_b and since the relay W is not now operated, it being operated only when the wiper 130 engages the first step terminal S_1 , the spare lamp 156 is lighted through the contacts P_b and W_a to provide the desired visual indication. Operation of the relay P also prematurely terminates the deadwood cycle and causes the pin setting machine to continue by spotting a new set of pins in the pin deck in the same manner as described in detail in the preceding section.

Section K—Operation of automatic cycling system in response to foul

In order to provide for proper operation in response to the commission of a foul the automatic cycling system is provided with a foul detector, indicated generally at 158, which operates a switch 160. The detector may be of any suitable construction adapted to close the switch 160 for a predetermined time after the commission of a foul.

The foul detector is located ahead of the ball detector so that whenever a foul is detected the switch 160 is closed before any other action occurs. Closing the switch 160 in turn energizes the relay F and thereby closes contacts F_b and F_d and opens contacts F_c .

Assume now that the ball thrown is the first ball thrown by the player in the instant frame. The rules of duckpin bowling provide that as a result of the foul all of the pins knocked down shall be resotted and that the ball is lost so that the player has two balls remaining in the frame.

As the ball passes the ball detector it breaks the light beam 68 and causes operation of the relays X and Y in the same manner as described in Section G to provide for stepping of the step switch wiper 130 to the S_1 terminal and also to provide for a period of simultaneous operation of the relays X and Y during which the contacts X_c and Y_d are simultaneously closed. This time however, contacts F_d are closed and contacts F_c are open so that the relay CR-1 rather than the relay CR-2 is operated as a result of the closing of X_c and Y_d . Operation of the relay CR-1 causes the pin setting machine to undergo a reset operation in the same manner as described in Section D. It will be noted however that this reset operation is initiated and completed without energizing the relay Z which controls the restoration of the stepping switch S , and that therefore after the completion of the reset operation the stepping switch wiper 130 remains in engagement with the first step terminal S_1 . The opening of the foul detector switch 160 may be controlled by a time delay device in the foul detector 158 or may have associated therewith a holding circuit which opens after the occurrence of a given event. In any case the switch 160 is opened before the machine is conditioned for receiving the next ball.

thrown by the player in the instant frame. The rules further provide that when a foul occurs on a second ball the pins knocked down shall be counted as though knocked down by the third ball and the ball is lost so that the player is through for the frame.

When this second ball passes the ball detector the X and Y relays are again operated to produce simultaneous closing of the contacts X_c and Y_d and stepping of the step switch wiper 130 to the second terminal S_2 . Again the simultaneous closing of the contacts X_c and Y_d together with the closed contacts F_d causes energization of the relay CR-1 to command a reset operation of pin setting machine. This time however the relay Z is operated due to the closed condition of the contacts F_b and the engagement of the wiper 130 with the second step switch terminal S_2 . As a result of this energization of relay Z the contacts Z_b are closed and a restore circuit is completed to the coil of the stepping switch which returns the wiper 130 to the home terminal S_0 , at which time the relay Z is released.

After the roll of the third ball in any frame, a reset cycle is performed in the manner described in Section H regardless of whether or not a foul has been committed.

The invention claimed is:

1. An automatic cycle control system for a bowling pin setting machine including first means operable in response to a command signal for causing said machine to perform a resetting operation and second means operable in response to a command signal for causing said machine to perform a deadwood operation, said automatic cycle control system comprising a counting mechanism movable to various successive positions to provide an indication of the ball count, cyclically operating means adapted when energized by a start signal to undergo a full cycle of operation and during said cycle of operation to produce a command signal normally transmitted to said second means to initiate a deadwood operation, means operable in response to the passage of a ball toward the pin deck associated with said pin setting machine for advancing said counting mechanism one position and for starting said cyclically operating means at such a time that said counting mechanism is advanced before said command signal is produced, another means operable when energized to cause restoration of said counting mechanism and transferral of the command signal produced by said cyclically operating means to said first means to initiate a resetting operation, and means operable in response to the movement of said counting mechanism to the position representative of a third ball for causing operation of said another means to cause restoration of said counting mechanism and transferral of the following command signal to said first means to initiate a resetting operation.

2. An automatic cycle control system for a bowling pin setting machine including first means operable in response to a command signal for causing said machine to perform a resetting operation and second means operable in response to a command signal for causing said machine to perform a deadwood operation, said automatic cycle control system comprising a counting mechanism movable to various successive positions to provide an indication of the ball count, first, second and third relays, means operable in response to the passage of a ball toward the pin deck associated with said pin setting machine for first advancing said counting mechanism one position and for immediately thereafter providing for a period of simultaneous operation of said first and second relays, means operable in response to said simultaneous operation of said first and second relays for issuing a command signal to said second means to initiate the performance of a deadwood operation, means operable in response to operation of said third relay for causing restoration of said counting mechanism and for transferring the command signal issued as a result of the simultaneous operation of said first and second relays to said first means to initiate a resetting operation, and means

operable in response to the movement of said counting mechanism to the position representative of a third ball for causing operation of said third relay prior to and during the immediately following period of simultaneous operation of said first and second relays to cause restoration of said counting mechanism and performance of a resetting operation.

3. An automatic cycle control system as defined in claim 2 further characterized by means for detecting a foul and responsive to such detection for transferring the command signal issued as a result of the following simultaneous operation of said first and second relays to said first means to initiate a reset cycle, said foul detecting means being further operable in association with said counting mechanism to cause operation of said third relay and thereby restoration of said counting mechanism in response to the detection of a foul on the second ball thrown by a given player in a frame.

4. An automatic cycle control system as defined in claim 2 further characterized by means operable during a deadwood operation for sensing the presence or absence of pins left standing by the immediately preceding ball and for providing an electrical signal representative of said presence or absence, means responsive to the signal representative of the absence of standing pins for terminating the deadwood operation, and means operable in response to such termination of the deadwood operation for causing said machine to perform a resetting operation and for energizing said third relay to cause restoration of said counting mechanism.

5. An automatic cycle control system as defined in claim 2 further characterized by means including a manually operable switch for causing simultaneous operation of said first, second and third relays and for thereby causing restoration of said counting mechanism and the initiation of a resetting operation in response to operation of said switch.

6. An automatic cycle control system as defined in claim 2 further characterized by means including a manually operable switch for causing simultaneous operation of said first and second relays and for thereby causing the initiation of a deadwood operation in response to operation of said switch.

7. An automatic cycle control system for a bowling pin setting machine, said control system including means for detecting the passage of a ball through the pin deck associated with said pin setting machine, a ball counting mechanism having a plurality of selectively energizable outputs, means associated with said pin setting machine and selectively operable in response to an initiating command signal to initiate and complete either a deadwood cycle of operation or a resetting cycle of operation of said machine, means operable in response to the detection of a ball by said detecting means for first shifting said ball counting mechanism from one output to another and for thereafter generating a command signal, and means responsive to the condition of energization of the outputs of said ball counting mechanism for conditioning said selectively operable means to cause said command signal to initiate either a deadwood cycle or a resetting cycle with the particular cycle chosen being dependent on said condition of energization of the outputs of said ball counting mechanism.

8. An automatic cycle control system for a bowling pin setting machine, said control system including means for detecting the passage of a ball through the pin deck associated with said pin setting machine, a ball counting stepping switch having a wiper and a plurality of output terminals sequentially engageable with said wiper, means associated with said pin setting machine and selectively operable in response to an initiating command signal to initiate and complete either a deadwood cycle of operation or a resetting cycle of operation of said machine, means operable in response to the detection of a ball by said detecting means for first stepping said wiper of said

stepping switch from one to another of said output terminals and for thereafter generating a command signal, and means responsive to the position of said wiper of said stepping switch for conditioning said selectively operable means to cause said command signal to initiate either a deadwood cycle or a resetting cycle with the particular cycle chosen being dependent on said wiper position.

9. An automatic cycle control system for a bowling pin setting machine as defined in claim 8 and further characterized by said stepping switch having four of said output terminals one of which is a home terminal and the other three of which are active step terminals, said means for conditioning said selectively operable means being operable to cause said command signal to initiate a deadwood cycle when said wiper is positioned on either the first or the second of said active step terminals and to initiate a resetting cycle when said wiper is positioned on the third of said active step terminals, and means operable after the initiation of said resetting cycle for restoring said wiper of said stepping switch to said home terminal.

10. An automatic cycle control system for a bowling pin setting machine as defined in claim 9 further characterized by means operable during a deadwood cycle for sensing the presence or absence of standing pins, and means operable in response to the detection of the absence of standing pins by said sensing means for interrupting the deadwood cycle, for thereafter causing said machine to follow through with a resetting operation and for restoring the wiper of said stepping switch to said home terminal.

11. An automatic cycle control system for a bowling pin setting machine, said control system including means for detecting the passage of a ball through the pin deck associated with said pin setting machine, a ball counting stepping switch having a wiper and a plurality of output terminals sequentially engageable with said wiper, means associated with said pin setting machine and including two input terminals, said latter means being operable in response to a command signal applied to one of said input terminals to initiate and complete a deadwood cycle of operation of said machine and operable in response to a command signal applied to the other of said input terminals to initiate and complete a resetting cycle of operation of said machine, means operable in response to the detection of a ball by said detecting means for stepping said wiper of said stepping switch from one to another of said output terminals and also operable in response to the same ball detection to generate a command signal, a cycle selection switch connected between said two input terminals and said command signal generating means for selectively connecting said command signal to either one of said two input terminals, and means responsive to the position of the wiper of said stepping switch for controlling the position of said cycle selection switch.

12. An automatic cycle control system for a bowling pin setting machine of the type including a vertically movable pin table and a separate horizontally movable distributor table and further including first means operable in response to a command signal for causing said machine to perform a resetting operation during which said distributor is moved into and out of a pin discharge position below said pin table and second means operable in response to a command signal for causing said machine to perform a deadwood operation during which said pin table is twice lowered to and raised from the associated pin deck, said automatic cycle control system comprising a counting mechanism movable to various successive positions to provide an indication of the ball count, cyclically operating means adapted when energized by a start signal to undergo a full cycle of operation and during said cycle of operation to produce a command signal normally transmitted to said second means to initiate a deadwood operation, means operable in response to the passage of a ball toward the pin deck associated with said pin setting machine for advancing said counting mecha-

nism one position and for starting said cyclically operating means at such a time that said counting mechanism is advanced before said command signal is produced, another means operable when energized to cause restoration of said counting mechanism and transferral of the command signal produced by said cyclically operating means to said first means to initiate a resetting operation, means operable in response to the movement of said counting mechanism to the position representative of a third ball for causing operation of said another means to cause restoration of said counting mechanism and transferral of the following command signal to said first means to initiate a resetting operation, means operable during the first rising movement of the pin table during a deadwood operation for sensing the presence or absence of pins left standing by the immediately preceding ball and for providing an electrical signal representative of said presence or absence, and means responsive to the signal representative of the absence of standing pins for terminating said deadwood operation as the pin table reaches the top of said first rising movement and for causing said machine to thereafter perform a resetting operation beginning with movement of said distributor table to its pin discharge position.

13. In an automatic bowling pin setting machine the combination comprising a pin table located above the pin deck of a bowling alley and movable vertically between raised and lowered positions, a distributor table adapted to receive and carry a full set of pins and movable with said full set of pins into and out of a pin discharge position located below the raised position of said pin table, a plurality of pairs of pin gripping members carried by said pin table with two gripping members of each of said pairs being movable relative to each other between relatively open positions at which they are adapted to fit loosely over the head of a bowling pin and relatively closed positions at which they are adapted to grasp and lift the head of a pin positioned therebetween, means for moving said pairs of gripping members in unison so that at any one time all of said pairs are either in their open positions or closed positions and for changing the state of said gripping members each time said pin table is lowered to either said pin deck or to said distributor table, first means operable in response to a command signal for causing said machine to undergo a deadwood cycle during which cycle said pin table is twice lowered to and raised from said pin deck with said gripping members initially in an open condition so that the pins standing on said pin deck are raised from said deck and then resotted, second means operable in response to a command signal for causing said machine to undergo a reset cycle during which said distributor table is first moved under said pin table and said pin table then lowered to said distributor table with said gripper members in an open condition followed by said pin table being thereafter raised, said distributor table thereafter being retracted from beneath said pin table and said pin table then being lowered and raised to spot a new set of pins on said pin deck, means for detecting the passage of a ball through said pin deck, a ball counting mechanism having a plurality of selectively energizable outputs, means operable in response to the detection of a ball by said detecting means for shifting said ball counting mechanism from one output to another and for generating a command signal, means responsive to the condition of energization of the outputs of said ball counting mechanism for selectively transmitting said command signal to either said first means or said second means to initiate either a deadwood cycle or a reset cycle, means operable during said deadwood cycle for sensing the number of pins lifted by said pin table during its first raising movement, and means operable in response to the detection of the absence of pins by said latter sensing means for interrupting said deadwood cycle when said pin table is at the top of its first raising movement and for thereafter causing said machine to follow through with a

resetting operation beginning with movement of said distributor table to said pin discharge position, said latter means including means for moving said gripping members from their closed to their open positions as said distributor table moves to its pin discharge position with the result that said pin table may be lowered directly to said distributor table to grip a new set of pins without first being lowered to and raised from said pin deck to shift the state of said gripping members.

14. In an automatic bowling pin setting machine the combination comprising a pin table located above the pin deck of a bowling alley and movable vertically between raised and lowered positions, a distributor table adapted to receive and carry a full set of pins and movable with said full set of pins into and out of a pin discharge position located below the raised position of said pin table, a plurality of pairs of pin gripping members carried by said pin table with the two gripping members of each of said pairs being movable relative to each other between relatively open positions at which they are adapted to fit loosely over the head of a bowling pin and relatively closed positions at which they are adapted to grasp and lift the head of a pin positioned therebetween, means for moving said pairs of gripping members in unison so that

5 at any one time all of said pairs are either in their open positions or closed positions and for changing the state of said gripping members each time said pin table is lowered to either said pin deck or said distributor table, and means for moving said gripping members from their closed to their open positions as said distributor table moves to its pin discharge position and when said pin table is in its raised position with said gripping members in their closed positions with the result that after said pin 10 table is lowered to said pin deck with its gripping members open and thereafter raised without taking with it any standing pins said pin table may be lowered directly to said distributor table to grip a new set of pins without first being lowered to and raised from said pin deck to shift the state of said gripping members.
